United States Patent

Des. 238,699

Patented Feb. 3, 1976

238,699

TOY COASTER

Anthony L. Hodges, 3123 41st St.,
San Diego, Calif. 92105

Filed July 31, 1974, Ser. No. 493,317

Term of patent 14 years

Int. Cl. D21—01
U.S. Cl. D34—15 AJ

Fig. 1

Fig. 2

Fig. 3

Fig. 4

FIG. 1 is a perspective view of a toy coaster, showing my new design;

FIG. 2 is a side elevational view thereof, as taken from the opposite side to that shown in FIG. 1;

FIG. 3 is a bottom plan view thereof; and

FIG. 4 is a rear elevational view thereof.

I claim:

The ornamental design for a toy coaster, substantially as shown.
